UNITED STATES PATENT OFFICE.

CHARLES TRAVALLED, OF NEW ROCHELLE, NEW YORK.

FLOOR AND CEILING CONSTRUCTION.

1,046,903.

Specification of Letters Patent. Patented Dec. 10, 1912.

Application filed January 24, 1912. Serial No. 673,218.

To all whom it may concern:

Be it known that I, CHARLES TRAVALLED, a citizen of the United States of America, and a resident of New Rochelle, Westchester county, State of New York, have invented 5 certain new and useful Improvements in Floor and Ceiling Construction, of which the following is a specification.

My invention relates to floor and ceiling 10 construction of the kind commonly known as fireproof construction, and more particularly to devices for supporting or suspending the ceilings and has for its object to provide a simple and efficient device of this 15 character adapted to readily receive and to prevent accidental removal of the usual ceiling bars.

My invention will be fully described hereinafter, and the features of novelty will be 20 pointed out in the appended claims.

Reference is to be had to the accompanying drawings in which—

Figure 1 is a sectional view of a part of a 25 floor and ceiling illustrating my improvement; Fig. 2 is a face view of my improved hanging device showing the ceiling bar in cross-section, and Fig. 3 is a detail perspective view of my invention.

In the drawings, 5 represents the lower 30 portion of an I-beam customarily used in constructions to which the present invention relates and which are covered either entirely or partially with concrete or other coalescent material 6 to render them fireproof. This 35 concrete or other coalescent material is maintained in position until it becomes set or hardened by means of temporary centering indicated in the drawings as 7 and 7a. In constructions to which the present invention 40 relates it has been found convenient to incorporate hangers or suspending devices on which the material forming the ceiling is carried or supported through the medium of ceiling bars or other means. In the present 45 case this hanger comprises a bar of metal 8 preferably flat and having a portion 9 which is preferably inclined provided with spaced apertures 10 and 10a near its upper free end. A clip 11 has a main portion 11a 50 passing through the aperture 10 and a return or hook portion 12 projecting through the aperture 10a and engaging the one upper surface of the lower flange 5a of the I-beam 5 as clearly shown in Fig. 1. The 55 main portion 11 of the clip initially extends in a substantially straight line, as indicated

in dotted lines in Fig. 1, and is bent around the opposite edge of the flange 5a to form a hook 13 after the clip has been passed through the apertures 10 and 10a and the hook 12 positioned on the flange 5a as described. The said clip is thus firmly secured in position on the I-beam and serves to lock the bar 8 in proper operative position. Adjacent to its lower end the bar 8 is provided 60 with an open recess 14 having a vertical wall 14a, upper walls 14b and 14c inclined in opposite directions or in other words diverging downwardly and a lower wall 14d curved about a center located approximately 65 at the center of the wall 14b. With this construction the open end 14e of the recess is smaller than the distance between the walls 14b, 14c and 14d for the purpose to be more 70 fully described hereinafter. This recess 14 is adapted to receive a ceiling bar 15 which 75 may be of any desired construction and is preferably of U-shape in cross-section and adapted to act as a support from which the ceiling may be hung in any usual and 80 convenient manner. This ceiling bar 15 is of a width greater than the open end or mouth 14e and can be introduced and removed from the recess 14 only by an angular 85 movement through said open end. That is, 90 the one edge of the ceiling bar 15 is first passed through the mouth 14e and raised until it is substantially in engagement with the wall 14b in which position the lower edge 95 of the bar 15 is slightly above the outer end 14a of the lower wall 14d, as clearly shown by dotted lines in Fig. 2. The said lower edge of said bar 15 may now be moved inwardly, the said movement being substantially in a curve and following the curve of the wall 100 14d until finally the bar 15 reaches the position shown in full lines in Fig. 2 of the drawings in which position said bar is firmly supported. The said bar 15 can only 105 be removed from the recess 14 by reversing the operation just described and cannot be taken therefrom in any other way, thus preventing accidental displacement and consequent destruction of or injury to the ceiling. It is of course to be understood that any well known means for securing the ceiling to the 110 bars 15 may be employed and further that a series of bars 15 and hangers 8 are used in the completed structure.

By bending the bar 8, as shown and described, the vertical leg or portion thereof will come closely adjacent to the point of

engagement between the one member 7^a and the member 7 of the temporary centering. It is therefore only necessary to slightly notch the member 7 of said centering, as indicated at 7^b, to accommodate the bar 8, an operation which results in an opening substantially filled by said bar, so that concrete or other coalescent material is prevented from escaping from said centering. In addition to this any pull or stress in a direction parallel with the vertical member of the hanger 8 will tend to move the inclined portion 9 on the edge of the flange 5^a of the beam 5 as a fulcrum. This will cause the aperture 10^a to tend to move away from said beam and the aperture 10 to move toward the same and will consequently compress the hook 12 toward the one portion of the flange 5^a and cause it to exert a greater gripping pressure thereon and at the same time will move the hook 13 into closer engagement with the opposite portion of said flange and consequently more firmly seat it thereon. It will thus be seen that the greater the strain on the ceiling bars the greater will be the gripping power of the clip on the flanges of the I-beams and the more firmly will the hangers be secured in position. A very rigid and firm support for the ceiling is thus secured. With the present construction the ceiling bars 15 are also easily placed in position and as before stated are absolutely incapable of accidental dislocation.

35 It is, of course, to be understood that the centering 7-7^a is removed after the concrete or other coalescent material 6 has set or become hardened.

40 Various changes may be made in the form shown and described within the scope of the claims without departing from the spirit of my invention.

I claim—

1. In a floor or ceiling construction, the 45 combination of a supporting beam, a hanger carried thereby and having a recess provided with a contracted opening located intermediate of the upper and lower ends of said recess and a bar adapted to be inserted 50 through said contracted opening into said recess and having a width greater than said contracted opening, said bar extending above and below said opening when in position in said recess.

55 2. In a floor or ceiling construction, the combination of a supporting beam, a hanger carried thereby provided with a recess having a top and bottom wall converging outwardly to form a contracted opening located

intermediate of the upper and lower ends 60 of said recess and a ceiling bar adapted to be inserted through said opening into said recess and having a width greater than said contracted opening and extending above and below the same when in position in said 65 recess.

3. In a floor or ceiling construction, the combination of a flanged supporting beam, a hanger having an inclined portion extending from said beam and a vertical depending portion, said inclined portion being provided with spaced apertures, means for securing said hanger on said beam, said means having spaced members each adapted to pass through an aperture of the hanger 75 and to respectively engage the upper and lower surfaces of the flange of said beam and ceiling supporting means carried by said hanger.

4. In a floor or ceiling construction, the 80 combination of a flanged supporting beam, a hanger provided with spaced apertures, a clip connected with said beam and bent upon itself to form spaced members each of which extends through one of said apertures 85 and engages the flange of said beam and ceiling supporting means carried by said hanger.

5. In a floor or ceiling construction, the 90 combination of a supporting beam, a hanger carried thereby and provided with a recess having a contracted opening, a vertical wall, an upper wall inclined upwardly from said opening, a second upper wall inclined downwardly from said first named upper wall to 95 said vertical wall, and a curved lower wall extending from said vertical wall to said opening, and a ceiling bar adapted to be inserted through said contracted opening and along said curved wall into said recess, 100 said ceiling bar being of greater width than said open end and of less width than the widest portion of said recess.

6. In a floor or ceiling construction, the 105 combination of a supporting beam, a hanger carried thereby and having an open ended recess formed therein, the lower wall of said recess being curved on the radius of a circle and a ceiling bar arranged to be inserted into the open end of said recess and moved 110 along the curved lower wall thereof.

In testimony whereof I have hereunto set my hand in the presence of two subscribing witnesses.

CHARLES TRAVALLED.
